PATCH-APPLYING MECHANISM FOR ENVELOPE MACHINES

Application filed October 20, 1927. Serial No. 227,466.

Envelopes are frequently lined with a fancy thin paper usually colored and carrying a pattern printed thereon in gold or some contrasting color which lining prevents the 5 contents of the envelope from being read through it or otherwise identified. These linings are of a great variety of forms and sizes. The paper is usually very flimsy and cheaply made and two pieces are hard to separate from each other, especially by suction, 10 several sheets often being lifted at the same time. The labor of fastening such a lining to an envelope is considerable and adds materially to its cost. The lining should be added to the envelope blank before it is folded 15 and stuck and the mechanism which I have invented and herein described is intended for that purpose, though it may be easily altered for the purpose of applying patches 20 to cover the opening of the so-called outlook envelopes, or for other like purposes.

It will readily be understood by reference to the drawings, in which it is shown in the best form of embodiment now known to me.

25 Fig. 1 is a cross section of such a mechanism on line 1—1 of Fig. 6 showing many of the parts in side elevation, and more particularly the lifter in position to lift an auxiliary blank or lining from a pile or stack thereof.

30 Fig. 2 is a similar view, the auxiliary blank having been lifted by the lifter and drawn a short distance off the pile.

Fig. 3 is also another sectional view showing the auxiliary blank applied to the main 35 or gummed envelope blank.

Fig. 4 is a sectional detail through the lifter showing the carrier receiving the auxiliary blank from the lifter and about to carry it to its place on the main blank as in 40 Fig. 2.

Fig. 5 is a sectional detail also through the lifter showing the auxiliary blank in transit from the lifter to its position on the main blank.

45 Fig. 6 is a front elevation of the mechanism.

Fig. 7 is a plan thereof.

Fig. 8 is a plan of a main or gummed envelope blank to which an auxiliary blank or 50 lining has been attached; and

Fig. 9 is a section on line 9—9 of Fig. 8.

Fig. 10 is a section on line 10—10 of Fig. 6.

The mechanism as shown is intended to be used with an ordinary envelope machine which has means for gumming and folding the envelope blank and also the usual central station between the gumming and folding mechanisms when the envelope blank is momentarily at rest, and it is at this point where the present mechanism may be conveniently used to apply the auxiliary blank or lining. As the means for gumming and folding the main blank to which the auxiliary blank is applied are well known in the art they are not shown herein nor described except to say that the gumming surface of the gummer may be of any desired shape, such for example, as to apply gum to the main blank at the points *a* in Fig. 8.

The principal features of the invention in its present embodiment are the lining table 1 on which the pile of auxiliary blanks or linings 2 rests, the sucker or lifter 3 by which the top auxiliary blank is lifted off the pile at the proper time and the rocking carrier 4 by which the auxiliary blank is carried to the main blank, being preferably assisted by the swinging supplemental carrier 5.

The lifter 3 and carrier 4 are both hollow and the lifter 3 is connected preferably by a flexible tube 131 with suitable suction producing mechanism of ordinary character (not shown) which is operated at suitable times for the purposes below described. The lifter 3 and the carrier 4 are each about as long 55 as the width of the auxiliary blank to be applied, the carrier being mounted on the hollow oscillating shaft 42 by means of short hollow pipes 6 and being provided with a longitudinal slot 7 through which the suction 60 from a flexible tube 141 may engage the auxiliary blank at the proper time. The lifter is also provided with a longitudinal slot 8 located to apply suction to the auxiliary blank, and means as described below are also 65 provided to adjust the angle at which the lifter 90 will strike the pile of auxiliary blanks.

The supplemental carrier 5 is arranged and controlled to swing under the auxiliary blank 95 when lifted assisting in its support and assist- 100

ing also in carrying and depositing the auxiliary blank in its final resting place on the main blank as will later be explained.

The lifter 3 co-operates with the carrier 4 and for this purpose is mounted and operated as follows.

9 is a rocker arm which is mounted on the rock shaft 10 supported on the machine and operates the frame by which the lifter 3 is carried, and by which it is lifted up and down to give the necessary lifting movement to the auxiliary blank. 11 is a forked plate, the forks of which carry blocks 12 through which passes a rod 13 having between the forks a friction roll 14 which rests on the rocker arm 9. The rod 13 extends laterally beyond one of the forks and on it is pivotally mounted a lever 15 to one end of which is attached a flat strip 16 at substantially right angles thereto, and to the other a rod 17 which extends down and is bent somewhat (see Fig. 6) to be pivotally attached to the rearward extension 18 of the lifter 3. The lifter 3 has a lug 19 extending below it by which it is pivotally attached at 20 to a lug 21 on the bottom of the forked plate 11 which has a broadened extension at the bottom as at 22 and is provided with a screw 23 to limit the upward movement of the free end of the lifter. 24 is a spring which is attached at one end to the arm 25 which is adjustable on the rod 17, the lower end of this spring being attached to the lug 19 by the screw 191. The upper end of the rod 17 is threaded above the lever 15 and is provided with adjusting and set nuts 26 so that its effective length may be adjusted. Guide ways 27 are mounted on the oscillating shaft 28 so that the frame as a whole may swing and also may be lifted by the rocker arm 9 or permitted to drop. The strip 16 passes down and is held in contact with roll 129 on rod 29 by means of spring 24. As the rocker arm 9 is caused to rise and fall by the rock shaft 10 it lifts the forked plate 11 in the ways 27 and the plate swings with the oscillating shaft 28 carrying with it the whole of the lifter frame. The lever 15 owing to its pivot has a rocking movement independent of the plate 11 and is rocked by means of the strip 16 which is fixedly attached to it and bears against the roll 129 on rod 29 thus controlling the angle of lifter 3 to the top one of the auxiliary blanks.

The rod 29 has a rocking movement such that the supplemental carrier 5 mounted on the arms 51 fast on the rod 29 will swing at the proper time, after the lifter has raised an auxiliary blank from the pile, and assist in holding up the raised blank while it is being carried by the carrier to the main gummed blank and will also assist in the inversion of the auxiliary blank prior to its deposit on the main blank. Rod 29 operates to control the angle of the lifter 3 by means of strip 16, lever 15 and rod 17, all as will

later be explained. When the rod 29 is at its low point as shown in Fig. 1 the strip 16 is approximately parallel to slide 11, thereby allowing slide 11 to be raised or lowered as the height of the pile varies without affecting the angle of the lifter 3. When rod 29 is in its upper position as shown in Figure 2 it allows lifter 3 to return to its normal position while depositing auxiliary blank on carrier 4, the suction of the lifter being then relieved and suction being then applied to the carrier. The carrier rocks with its hollow shaft 42 taking the auxiliary blank from the lifter and carrying it by suction and laying it on the main blank, the supplemental carrier 5 coming up beneath the auxiliary blank as it is carried and assisting in depositing it on the main blank as will presently be explained.

These various parts may be operated in a simple manner as indicated in the drawing where 30 indicates the frame of an envelope machine, on which the various parts of my mechanism may be mounted at the central station, and in which the carriage or other parts carrying the blank runs. 31 is a cam shaft carrying three cams 32, 33 and 52 having the usual cam rolls 34, 35 and 53. The cam roll 34 is connected by the link 36 with crank mechanism 37 on shaft 10 to give it an oscillating movement. The cam roll 35 is connected by link 38 with the crank mechanism 39 on shaft 28 to give it an oscillating movement.

The arms 41 and 41^a are loosely mounted on shaft 28. They are joined fixedly together by rod 29 and are connected to crank pin 43 on gear 44 by link 54 to give the rod an oscillating movement. Motion is given to gear 44 from gear 45 on the same shaft with it and in mesh with gear 46 on stub shaft 48 supported by one of the hangers 49 from a bracket 50 on the frame of the machine. The shaft 48 carrying the gear 46 is given an oscillating movement by means of cam 52, cam roll 53 on cam lever 56 and link 54 connecting cam lever 56 with gear segment 55 (see Fig. 10). The gear 44 is in mesh with gear 420 on tube 42 and oscillates it. The cam 52 and cam roll 53 are held together in any usual way. All lost motion between the tube 42 and the chain of gears through which the tube is oscillated is taken up by the tension of a coiled spring 143 arranged upon the end of the tube one end of which is attached to a collar 144 on the tube and the other to a collar 144' on the tube but which is fixed to the frame.

The general operation is as follows: It will first be understood that the frame by which the lifter 3 is carried and controlled and which comprises the plate 11 slidable in the ways 27, together also with the lever 15, the strip or bearing 16, and the rod 17, though elevated by the lifting of the rocker arm 9 on the rocking of the shaft 10 is permitted

to drop by gravity on the lowering of the rocker arm, and the permitted drop or extent of lowering of the frame is determined by contact of the lifter 3 with the pile of auxiliary blanks 2 in order that the lifter 3 may have proper contact with the top one of the pile of blanks as the height of the pile may vary, the lowering of the rocker arm 9 being sufficient at all times to permit of this action.

10 Referring first to Fig. 1 where the lifter 3 is shown in contact with the top one of the pile of blanks adjacent the edge thereof and just about to lift one of the blanks:

15 At this time the frame carrying the lifter 3 will have been turned, by the turning of the shaft 28, to a position where the frame when lowered will bring the lifter into contact with the top one of the pile of blanks adjacent one edge thereof leaving free the body of the blank lying back of said edge. The lifter 3 will then be occupying a position turned away from the stop 22 against which it has normal bearing so that its suction face may be brought into proper contact with the edge of the auxiliary blank for lifting it. The turning of the lifter 3 is effected by the lowering of the shaft 29 which carries the roll 129 against which the strip 16 has normal bearing. The lowering of the shaft 29 acts through the strip 16 to turn the lever 15 and thereby elevate the outer end of the lifter turning it, the distortion of the spring 24 permitting of such turning. The turned position of the lifter 3 is limited by the amount the shaft 29 is lowered and the shaft 29 is lowered in an amount not only sufficient to turn the lifter so that its suction side or face will have proper contact with the auxiliary blank on the top of the pile but to a position also where the strip 16 will lie substantially parallel with the slide 11 of the lifter-carrying frame so that as the frame is lowered, to move the lifter into contact with the pile, there will be no angular change or turning of the lifter as the height of the pile may vary. That is, the lifter has not only been turned into a position to properly contact with the top one of the pile of blanks, but the lifter is at the same time so held and controlled that its angular or turned position will be maintained irrespective of the height of the pile of blanks as the lifter-carrying frame is raised or lowered at this time.

50 At this same time the supplemental carrier 5 which assists in the carrying of the blank elevated by the lifter will have been moved into a forward out-of-the-way position. This supplemental carrier is borne by arms 42 secured to the rod 29 so that as the rod 29 is turned down for controlling the position of the lifter as just explained, it also operates to turn the supplemental carrier 5 into its out-of-the-way position as aforesaid. At this same time, also, the carrier 4 which takes the auxiliary blank from the lifter and lays it upon the main or gummed envelope blank, as will presently be explained, is returning after having deposited an auxiliary blank upon the main or gummed envelope blank and is then occupying an out-of-the-way position. With all the parts thus positioned the rocker arm 9 will be lowered by the rocking of the shaft 10 sufficiently to allow of the dropping of the frame carrying the lifter 3 to where it will have contact with the top one of the pile of auxiliary blanks as aforesaid. Such dropping of the lifter-carrying frame will continue slightly further than as shown in Fig. 1 in order that the slot 8 in the lifter through which suction is applied to the blank for lifting it, will be brought into close proximity to the edge of the blank.

55 When the lifter is thus brought into close proximity with the edge of the blank suction is applied to the lifter. Thereupon the lifter-carrying frame begins to rise by the elevation of the rocker arms 9, and the lifter lifts the top blank from the next adjacent blank in the pile of auxiliary blanks. At this time the lifter-carrying frame will be turned by the turning of the shaft 28 and the lifter moved forward away from the edge of the pile of blanks, substantially as shown in Figs. 2 and 4. As the lifter thus moves forward it is allowed to resume its normal position contacting with the stop 22. This is permitted by raising the shaft 29 which releases the strip 16 when the spring 24 will operate to throw the lifter into contact with the stop.

60 The elevation of the shaft 29 operates also to throw the supplemental carrier 5 inward beneath the lifted blank to a position just back of the edge thereof where it is being retained by the suction of the lifter 3. At this time also, following the supplemental carrier 5, the carrier 4 will be turned back to a position where its slot 7 through which suction is applied to the auxiliary blank for carrying it, will be positioned just beneath the edge of the blank which has been lifted and borne by the lifter as aforesaid. Thereupon the lifter will be relieved of all suction and suction will be applied to the carrier 4 and the auxiliary blank made to adhere to it along its edge, all substantially as shown in Figs. 2 and 4. Thereupon the carriers 4 and 5 will be moved forward, the carrier carrying the auxiliary blank drawn off the pile of blanks and the supplemental carrier 5 assisting in the support of the blank as it is being carried, the forward movement of the supplemental carrier being obtained by a further downturning of the shaft 29 to which it is fixed, all substantially as shown in Fig. 5.

65 Following this movement, the carrier 4 will turn downward carrying the auxiliary blank with it on account of its engagement with the seized edge thereof with the body

of the blank left free trailing behind until the carrier has reached a downturned position where it will have inverted the seized edge of the auxiliary blank and applied it to the gummed edge of the main blank. Such turning or inversion of the auxiliary blank along the edge thereof tends to so bend it that the entire trailing body of the auxiliary blank will then turn over or become inverted and roll down into place onto the main or gummed envelope blank. This action takes place on account of the tendency of the bent auxiliary blank to straighten assisted by gravity, and is facilitated in case the auxiliary blank is of thin material possessing little body stiffness, by the supplemental carrier 5 which assists in turning or inverting it, for as the carrier 4 tends to turn downward the supplemental carrier 5 will be moved forward by the further downward movement of the shaft 29, with the effect of throwing the body of the blank over, thereby assisting in its turning or inversion.

The operation of depositing the auxiliary blank having thus been effected, the main blank with the auxiliary blank applied to it then passes to the folding box in the ordinary operation of the machine and is there folded, the operations incident to folding acting also to firmly press the auxiliary blank to the main blank. At the same time, after the deposit of the auxiliary blank on the main blank the carrier 4 is relieved of suction and the operating parts made to resume a position substantially as shown in Fig. 1, and the operation repeated as other envelope blanks are brought to the central station.

While the sequence of operation of the parts is thus described as though intermittent, their operation in point of fact is continuous, one step following another with great rapidity and there is no break.

The supplemental carrier 5 which assists in carrying the auxiliary blanks may be dispensed with if the blanks carried are of material having some stiffness and inherently capable of turning or inversion when borne by the carrier 4 as aforesaid. When the blank is thin having but little body stiffness and elasticity, as is often the case, then the supplemental carrier 5 is desirable, if not necessary.

Reference has already been made to the fact that the lifter 3 contacts with the top one of the pile of blanks adjacent the edge thereof so that its suction port 8 will have operative effect to lift the blank at a point immediately adjacent its edge. Owing to the fact that the auxiliary blank or lining is sometimes of very thin light material a strong suction applied to the top one of a pile of blanks is apt to lift more than one blank. By application of the suction, however, to the edge of the blank but one blank will be lifted at a time because the lifting of the edge of

the blank will tend to break the partial vacuum existing between the top blank and the next one below it. By adjustment of the set nuts 26 on the upper end of the rod 17 the lifter 3 may be angularly positioned for most effectively lifting the top one of the pile of blanks when applied to it.

While it will be evident to those skilled in the art that my invention may be differently embodied I have shown and described it above in the best form now known to me and I realize that it may be varied without departing from its essence.

What I claim as my invention is:—

1. In mechanism of the class described for applying an auxiliary blank to a gummed main blank, the combination comprising an oscillating carrier for the auxiliary blank adapted to have carrying engagement with the auxiliary blank along only one edge thereof leaving free the body of the blank lying back of said edge, and means for operating the carrier for depositing the auxiliary blank on the main blank whereby the engaged edge of the auxiliary blank will become inverted preliminary to its application by the carrier to the main blank and afterward the free trailing body of the auxiliary blank lying back of said edge will become inverted and deposit itself on the main blank.

2. In mechanism of the class described for applying an auxiliary blank to a main blank, the combination comprising an oscillating suction carrier for the auxiliary blank adapted to have carrying engagement with the auxiliary blank on the under side thereof along only one edge leaving free the body of the blank lying back of said edge, and means for operating the carrier for depositing the auxiliary blank on the main blank whereby the engaged edge of the auxiliary blank will become inverted preliminary to its application by the carrier to the main blank and afterward the free trailing body of the auxiliary blank lying back of said edge will become inverted and deposit itself on the main blank.

3. In mechanism of the class described for applying an auxiliary blank to a main blank, the combination comprising a feed for the auxiliary blanks, a carrier for the auxiliary blanks as they are fed, said carrier being adapted to have carrying engagement with each fed auxiliary blank along only one edge thereof leaving free the body of the blank lying back of said edge, means for mounting the carrier to reciprocate along an arcuate path between the point of feed of the auxiliary blanks and the main blank whereby as the carrier passes from the point of feed to the main blank said engaged edge portion of the auxiliary blank will become inverted by the carrier and deposited upon the main blank and the free trailing body of the auxiliary blank lying back of the deposited edge portion thereof will become inverted and de-

posit itself on the main blank, and means for reciprocating the carrier.

4. In mechanism of the class described for applying an auxiliary blank to a main blank, the combination comprising a feed for the auxiliary blanks, a suction carrier for the auxiliary blanks as they are fed, said carrier being adapted to have carrying engagement with each fed auxiliary blank on the under side thereof along only one edge leaving free the body of the blank lying back of said edge, means for mounting the carrier to reciprocate along an arcuate path between the point of feed of the auxiliary blanks and the main blank whereby as the carrier passes from the point of feed to the main blank said engaged edge portion of the auxiliary blank will become inverted by the carrier and deposited upon the main blank and the body of the auxiliary blank lying back of the deposited edge portion thereof will become inverted and deposit itself on the main blank, and means for reciprocating the carrier.

5. In mechanism of the class described for applying an auxiliary blank to a gummed main blank, the combination comprising a carrier for the auxiliary blank adapted to have carrying engagement with the auxiliary blank along the edge thereof, means for operating the carrier for depositing the auxiliary blank on the main blank whereby the engaged edge of the auxiliary blank will become inverted preliminary to its application by the carrier to the main blank and afterward the body of the auxiliary blank back of said edge will become inverted and deposit itself on the main blank, and means assisting in inverting the body of the auxiliary blank whereby it may deposit itself as aforesaid on the main blank.

6. In mechanism of the class described for applying an auxiliary blank to a main blank, the combination comprising a suction carrier for the auxiliary blank adapted to have carrying engagement with the auxiliary blank on the under side thereof along its edge, means for operating the carrier for depositing the auxiliary blank on the main blank whereby the engaged edge of the auxiliary blank will become inverted preliminary to its application by the carrier to the main blank and afterward the body of the auxiliary blank back of said edge will become inverted and deposit itself on the main blank, and means assisting in inverting the body of the auxiliary blank whereby it may deposit itself as aforesaid on the main blank.

7. In mechanism of the class described for applying an auxiliary blank to a main blank, the combination comprising a feed for the auxiliary blanks, a carrier for the auxiliary blanks as they are fed, said carrier being adapted to have carrying engagement with each fed auxiliary blank along its edge,

means for mounting the carrier to reciprocate along an arcuate path between the point of feed of the auxiliary blanks and the main blank whereby as the carrier passes from the point of feed to the main blank said engaged edge portion of the auxiliary blank will become inverted by the carrier and deposited upon the main blank and the body of the auxiliary blank lying back of the deposited edge portion thereof will become inverted and deposit itself on the main blank, and means for reciprocating the carrier, and means assisting in inverting the body of the auxiliary blank whereby it may deposit itself as aforesaid on the main blank.

8. In mechanism of the class described for applying an auxiliary blank to a main blank, the combination comprising a feed for the auxiliary blanks, a suction carrier for the auxiliary blanks as they are fed, said carrier being adapted to have carrying engagement with each fed auxiliary blank on the under side thereof along its edge, means for mounting the carrier to reciprocate along an arcuate path between the point of feed of the auxiliary blanks and the main blank whereby as the carrier passes from the point of feed to the main blank said engaged edge portion of the auxiliary blank will become inverted by the carrier and deposited upon the main blank and the body of the auxiliary blank lying back of the deposited edge portion thereof will become inverted and deposit itself on the main blank, and means for reciprocating the carrier, and means assisting in inverting the body of the auxiliary blank whereby it may deposit itself as aforesaid on the main blank.

9. In mechanism for applying auxiliary blanks arranged in pile to successively fed main blanks, the combination comprising a suction lifter for the auxiliary blanks, a frame carrying the lifter having a permitted gravity drop, means for pivotally mounting said frame whereby the lifter may be moved between an auxiliary blank lifting position and a delivery position on turning the frame, means for intermittently lifting said frame permitting of an intermittent gravity drop thereof, means carried by said frame for changing the angular turned position of the lifter, and means for taking an auxiliary blank from the lifter when in its delivery position and applying it to a main blank.

10. In mechanism for applying auxiliary blanks arranged in pile to successively fed main blanks, the combination comprising a suction lifter for the auxiliary blanks, a frame carrying the lifter having an intermittent gravity drop, means for pivotally mounting said frame whereby the lifter may be moved between an auxiliary blank lifting position and a delivery position on turning the frame, means for intermittently lifting said frame permitting of an intermittent

- gravity drop thereof, means for releasably maintaining the lifter in a normal angularly-turned position, means for changing the angularly turned position of the lifter and 5 for maintaining its angularly-turned position when the lifter is moved into its auxiliary blank lifting position, and means for taking an auxiliary blank from the lifter when in its delivery position and applying it to a main blank.
- 10 11. In mechanism for applying auxiliary blanks arranged in pile to successively fed main blanks, the combination comprising a suction lifter for the auxiliary blanks, a frame carrying the lifter having an intermittent gravity drop, means for pivotally mounting said frame whereby the lifter may be moved between an auxiliary blank lifting position and a delivery position on turning 15 the frame, means for intermittently lifting said frame permitting of an intermittent gravity drop thereof, means for normally holding the lifter in a determinate angularly-turned position, means for changing the angularly turned position of the lifter as the lifter is moved into and away from its auxiliary blank lifting position, and means for taking an auxiliary blank from the lifter when in its delivery position and applying it to a main blank.
- 20 12. In mechanism for applying auxiliary blanks arranged in pile to successively fed main blanks, the combination comprising a blank-lifting means for successively lifting auxiliary blanks from the pile, blank-carrying means for successively taking the auxiliary blanks from the blank-lifting means and depositing them on the main blanks as they are successively fed, a supplemental carrier, 25 and means for moving the supplemental carrier in a path between said blank-lifting means and said blank-carrying means whereby said supplemental carrier will assist in the control of the auxiliary blanks lifted and carried thereby.
